UNITED STATES PATENT OFFICE.

FREDERICK LEOPOLD, JR., OF HARMONVILLE, PENNSYLVANIA, ASSIGNOR TO LEE RUBBER & TIRE CORPORATION, OF CONSHOHOCKEN, PENNSYLVANIA, A CORPORATION OF NEW YORK.

DESIGN FOR A TIRE CASING.

Application filed January 31, 1928. Serial No. 25,104. Term of patent 14 years.

To all whom it may concern:

Be it known that I, FREDERICK LEOPOLD, JR., a citizen of the United States of America, residing at Harmonville, in the county of Montgomery and State of Pennsylvania, have invented a new, original, and ornamental Design for Tire Casings, of which the following is a specification, reference being had to the accompanying drawings, forming part thereof, in which—

Figure 1 is a plan view of my present

design embodied in an automobile tire casing; and

Figure 2 is a fragmentary, transverse sectional view taken on the line 2—2 of Figure 1.

I claim:

The ornamental design for a tire casing substantially as shown.

In testimony whereof I subscribe my signature.

FREDERICK LEOPOLD, JR.
